[57] CLAIM

The ornamental design for a link for jewelry chain,
substantially as shown and described.

DESCRIPTION

FIG. 1 is a top plan view of a link for jewelry chain
showing my new design, the bottom being plain;

FIG. 2 is a front elevational view;

FIG. 3 is a rear elevational view; and

FIG. 4 is a left side elevational view, the right side being
a mirror image.
